UNITED STATES PATENT OFFICE.

SEYMOUR W. BONSALL, OF NEW YORK, N. Y.

LOCKING DEVICE.

No. 808,188.

Specification of Letters Patent.

Patented Dec. 26, 1905.

Application filed June 24, 1904. Serial No. 213,979.

To all whom it may concern:

Be it known that I, SEYMOUR W. BONSALL, a citizen of the United States, residing in the city, county, and State of New York, have invented a certain new and useful Improvement in Locking Devices, of which the following is a specification.

This invention has particular relation to means for securing wardrobe-trunks of the general type shown, for instance, in my Letters Patent No. 604,346, dated May 17, 1898, wherein the cover to be locked consists of two parts or flaps hinged at the ends of the trunk and coming together near the middle thereof. It is not to be understood, however, that this invention is limited to its application to trunks of the type mentioned. Trunks of this type have been hitherto made with a lock at the middle of the overlapping edges of the two flaps, supplemented by spring-catches or equivalent devices at the side of the flaps to prevent springing open by bending up at the corners. This mode of attachment involves operation of at least three devices in unlocking the trunk and usually in locking it as well.

The present invention relates to an improved form of lock so constructed that the middle and both sides are all simultaneously secured by one operation.

My invention is illustrated in its preferred form in the accompanying drawings, wherein—

Figure 1 is a side view of a wardrobe-trunk of the type above mentioned provided with my improved device. Fig. 2 is an elevation of a portion of the inside of the flaps when closed, and Fig. 3 is an enlarged sectional detail view of the lock-hasp on the line x x of Fig. 2.

The trunk (shown at 1) is provided with a top flap 2 and a bottom flap 3, both of which are hinged to the trunk and come together at the middle. The usual guide-pins 4 are provided on the two flaps and are adapted to enter the sockets 5 and insure the proper steadyng of the covers when closed. The usual hasp of the middle lock is shown at 6, and instead of being hinged to the outside of the upper flap 2, as has been commonly the practice hitherto, this hasp is rigidly fastened to a polygonal bar 7, extending entirely across the flap 2 on its inner surface. The hasp is preferably fastened by means of a tight-fitting metal strap 8, and the bar 7 turns in metal bearings 9, fastened to the inner sur-

face of the flap 2. The material of the flap 2 is cut out sufficiently to allow the upper end of the hasp 6 to move in and out, as shown in the two positions illustrated in Figs. 1 and 3. 60

The bar 7 extends to a point just outside of the side valances 10, and at the two extremities of the bar 7 there are rigidly secured two hooks 11 and 12, preferably of the form shown in Fig. 3. I prefer to closely confine 65 the sheet-metal valances 10 between the hooks 11 and 12 and appropriate sleeves or bushings 13, which are introduced between the valances and the outermost bearings 9, so as to abut upon each. By thus confining 70 the valances they are prevented from bending, and the strength of the trunk is increased. These valances overlap the edges of the box or trunk in the usual manner.

Over each hook 11 and 12 I place a casing 75 or guard 14, and a similar guard 15 is supplied, which is fixed to the sides of the trunk, fitting against and opposite to the guards 14. A pin 16 is firmly secured within each of the guards or casings 15 and is so placed that as 80 the hooks 11 and 12 revolve upward they first engage with said pins and then by virtue of their form, as illustrated, tend to embrace the same more and more closely, and thus to draw cover 2 more and more firmly into place, 85 until at last the position is reached which is shown in Fig. 3.

It will be seen that when the trunk is to be closed and the top flap 2 has been pressed substantially into place the mere closure of 90 the hasp 6 preparatory to locking the middle lock is sufficient to operate the hooks 11 and 12, so as to firmly secure the sides and corners of the top flap 2. Since this flap overlaps the lower one, both covers are secured at 95 once. Thus the act of locking the trunk by the middle lock also locks it at the sides and corners of the covers.

A number of changes can be made in this device without departing from the scope of 100 my invention, and I am not to be limited to the details herein shown and described.

What I claim is—

1. In a device of the class described, a cover, valances on the sides thereof, a transverse 105 bar revolubly supported within said cover and extending outside of said valances, hooks fixed on the ends of said bar, and a lock-hasp extending through an appropriate opening in said cover and rigidly fixed to said bar, substantially as described.

2. In a device of the class described, a cover,

valances on the sides thereof, a transverse bar revolvably supported within said cover and extending outside of said valances, a bearing for said bar near each valance, a sleeve fitting snugly between each of said bearings and said valances, hooks outside said valances fixed to the ends of said bar and a lock-hasp fixed on said bar, substantially as described.

3. In a device of the class described, a box, a cover therefor, catchers outside the box, hooks pivoted outside said cover, so shaped

as to draw the box and cover together as said hooks are forced onto said catches, a lock-hasp on the cover and connecting means between the hasp and said hooks for operating the latter by movement of the former, substantially as described. 15

SEYMOUR W. BONSALL.
